CRYSTALLIZING APPARATUS

Jacques Walter, Mulhouse-Brunstatt, France, assignor to Mines Domaniales de Potasse d'Alsace, Mulhouse, France

Application November 20, 1931, Serial No. 576,420
In France December 23, 1930

17 Claims. (Cl. 23—273)

My invention relates to improvements in apparatus for producing crystallization in a vacuum. The object of this type of apparatus is to ensure cooling, under conditions of continuous running, 5 by boiling, under reduced pressure, warm concentrated brine in which that lowering of temperature causes the formation of crystals.

To this effect, the brine is generally caused to go through several crystallizing elements in 10 succession. Circulation between these various elements is usually effected by siphoning; however, such a process leads to serious difficulties in the operation. In particular, the apertures for connecting the elements to one another are 15 subject to obstruction by salt deposits and, as said elements are grouped in series, the stopping of one means the stopping of the whole plant. Moreover, said elements themselves get covered with saline incrustations, the elimination of 20 which entails special and expensive care. Finally, the level of the brine in the various elements does not remain steady and serious inconveniences also derive from this cause.

It has already been suggested to produce a 25 forced circulation between the various elements, but the apparatus constructed up to the present to this effect present the same defects as ordinary apparatus without forced circulation.

The essential characteristic of the apparatus 30 according to my invention consists in the branching of a certain number of crystallizing elements to a main pipe connecting the brine inflow receiver to the outflow receiver, each element of crystallization being provided with a pump, or 35 propeller, which draws liquid from the main pipe and discharges to the element under consideration brine issuing partly from said element and partly from the preceding element.

The outlet pipe of the pump opens either above 40 the level of the brine in the element of crystallization, or below said level, and the capacity of the pump is chosen greater than the maximum output of the element of crystallization.

The device according to my invention presents, amongst others, the following advantages:

- (1) In case of one of the elements of crystallization getting blocked, said element can be isolated and cleaned without the operation of the rest of the plant being affected in any way;
- (2) The levels are stabilized almost exactly to the level of the overflow of the outlet vessel without being influenced by the crust which may form on the nozzle of the discharge pipe of one of the pumps;
- (3) Risks of stoppage of the pipes and ele-

ments through crystallization are greatly diminished by adopting a system of forced circulation with a high rate of flow, in closed circuit, for each element of crystallization;

(4) It is possible to vary, between rest and full running, the flow received and yielded by the element of crystallization without the latter getting out of order; in particular, the same output may be maintained in case of partial obturation of the discharge pipe of the pump, 10 the latter running, then, at full capacity;

(5) The repeated passing through the boiling zone of the same brine loaded with crystals, which results from the greater rate of flow of the propeller as compared with that of the element 15 of crystallization, results in an increase in the volume of the grains.

Preferred embodiments of my invention will be hereinafter described with reference to the accompanying drawing given merely by way of 20 example and in which:

Fig. 1 is a diagram, in vertical section, of the crystallizing apparatus according to my invention;

Fig. 2 is a similar view of another embodiment 25 of my invention.

In the drawing, the dotted lines show the path followed by the mother-water, while the dot and dash lines show the passage of the brine.

The hot brine, previously concentrated, is 30 placed in the inflow vessel 1, which is connected to the outflow vessel 2 by a main pipe 3. To said main pipe are connected a certain number of elements of crystallization, three for instance, namely, elements 4, 5 and 6. Pipes 7, 8 and 9 35 are disposed between said elements and the main pipe.

To each element of crystallization corresponds a pump, or propeller, 10, 11 and 12 respectively, 40 which draws the brine from the main pipe before the outlet pipe of the corresponding element. The discharge pipes of said pumps are provided, at their extremities, with special nozzles 16, 17 and 18, which open slightly above the level of the brine in the element under consideration. Said level corresponds to the vacuum existing in the upper part of said element.

Elements 4, 5 and 6 are connected, at their upper extremities, through conduits 19, 20 and 21, to a vacuum pump 40, in order that the boiling 50 of the brine may take place under reduced pressure. Valves are provided to allow of stopping the vacuum at will in one or more of said elements, for instance, when it is necessary to clean them.

The vapours emitted by elements 4, 5, 6 are condensed in apparatus which, in the example given, work by direct contact and are designated by reference characters 22, 23 and 24 respectively. In each condenser, the vapours are met by the mother-water, which is brought through branch pipes 26, 27, 28, which are connected to a main pipe 25; said mother-water is returned to said main pipe through branch pipes 29, 30, 31; main pipe 25 connects vessel 32 to outflow vessel 34 through the condenser and it receives the mother-water through a pipe 33.

The exhausted brine runs off through overflow 35, while the salt crystals run out through pipe 36.

In the second embodiment of my invention shown in Fig. 2, the organs correspond to those shown in Fig. 1, being designated by the same reference numbers. Discharge pipes 13, 14 and 15 open within the brine contained in elements 4, 5 and 6, at a short distance below the free surface of the liquid.

It should be noted that the height to which the brine is conveyed is not very great and corresponds to a rather small consumption of energy. In the embodiment according to which injection takes place from the top (Fig. 1), it is equal to the difference of level between the nozzle and the liquid situated below, increased by the loss of head in the circuit. In the embodiment according to which the feed takes place from the bottom (Fig. 2), the manometrical height to be won, is only equal to the loss of head in the circuit. However, in order to insure a constant flow, even in the case of an abnormal resistance, the feeding capacity of the pumps is chosen substantially greater than the one above stated.

It will also be realized that the difference of levels between the inflow and the outflow vessels, which are near each other, only depends on the loss of head in the main pipe. It is very slight, approximating, for instance, a few centimetres.

Instead of direct contact condensers, I could use surface condensers, or mixed condensers, and cause ordinary water, instead of mother-water, to flow through a part of the apparatus.

While I have disclosed what I deem to be preferred embodiments of my invention, I do not wish to be limited thereto, as there might be changes made in the construction, disposition and form of the parts, without departing from the principle of my invention as comprehended within the scope of the appended claims.

In the following claims I have used the word "circuit" to designate the series of pipes and apparatus through which brine withdrawn from main pipe 3 is caused to flow before being fed back to said main pipe. For instance, such a circuit consists of pipe 13, nozzle 16, a portion of apparatus 4 and pipe 7. I have also used the expression "connected in parallel with said main pipe", by analogy with the electrical term, to state that all these circuits are independently connected with said main pipe and are not in series with one another.

What I claim is:

1. A crystallizing apparatus of the type described, comprising in combination, an inlet tank for the hot brine, an outlet tank, a main pipe for connecting said inlet tank to said outlet tank, a plurality of crystallizing elements, two pipes for connecting each crystallizing element directly to said main pipe so as to form a circuit for each of said crystallizing elements which

comprises, a part of said crystallizing elements, one of these two pipes, a portion of the main pipe, and the other one of the two pipes, a pump in said circuit for causing the brine to flow through said circuit and means for creating a vacuum in each of these elements. 5

2. A crystallizing element of the type described, comprising in combination, an inlet tank for the hot brine, an outlet tank, a main pipe connecting said inlet tank to said outlet tank, a plurality of crystallizing elements located above said main pipe, an inlet pipe for each element for connecting said main pipe to the intermediate part of said element, an outlet pipe for each element for connecting the bottom 15 thereof to said main pipe, said outlet pipe opening into said main pipe at a certain distance, in the direction of the outlet tank, from the point at which the corresponding inlet pipe branches off from the main pipe, 20 a pump in each inlet pipe for discharging liquid from the main pipe into the corresponding crystallizing element, and means for producing a vacuum in each of said crystallizing elements.

3. A crystallizing apparatus according to claim 2, further comprising a nozzle at the upper end of each inlet pipe located above the level of the hot brine in said element.

4. A crystallizing apparatus according to claim 2, in which each inlet pipe opens into the corresponding crystallizing element below the level of the brine in said element. 30

5. A crystallizing apparatus according to claim 2, in which the capacity of each pump is chosen substantially greater than the maximum output 35 of the corresponding crystallizing element.

6. A crystallizing apparatus according to claim 2, in which the crystallizing elements consist of upright vessels, said apparatus further comprising a condenser at the upper end of each of said vessels 40 for condensing the vapours issuing from the hot brine.

7. A crystallizing apparatus according to claim 2, in which the crystallizing elements consist of upright vessels, said apparatus further comprising 45 a direct contact condenser in the upper end of each of said vessels, and means for feeding said mother-water to said condenser.

8. A vacuum crystallizing apparatus of the type described, which comprises in combination, a main 50 pipe, means for causing brine to flow continuously through said main pipe, a plurality of separate circuits for the brine connected in parallel with said main pipe, liquid propelling means for causing the brine to circulate through said circuits, 55 and means for applying a vacuum to a portion of each of said circuits for evaporating the brine.

9. A vacuum crystallizing apparatus of the type described, which comprises in combination, a main 60 pipe, means for causing brine to flow continuously through said main pipe, a plurality of separate circuits for the brine connected in parallel with said main pipe, liquid propelling means for causing the brine to circulate through said circuits, vacuum producing means, and means for connecting a portion 65 of each of said circuits in parallel with said vacuum producing means.

10. A vacuum crystallizing apparatus of the type described, which comprises in combination, a main pipe, means for causing brine to flow continuously through said main pipe, a plurality of separate circuits for the brine connected in parallel with said main pipe, liquid propelling means for causing the brine to circulate through said circuits, condensing means in each of said circuits, a 75

main for feeding refrigerating liquid to all of said condensing means, vacuum producing means, and means for connecting a portion of each of said circuits in parallel with said vacuum producing

5 means

11. A vacuum crystallizing apparatus of the type described, which comprises in combination, a main pipe, means for causing brine to flow continuously through said pipe, a plurality of separate circuits 10 for the brine connected in parallel with said main pipe, liquid propelling means for causing the brine to circulate through said circuits, condensing means in each of said circuits, a main for feeding refrigerating liquid to all of said condensing 15 means, vacuum producing means, and a plurality of pipes connected in parallel with said vacuum producing means and opening each into one of said circuits respectively at a part thereof remote from the first mentioned main.

20 12. A vacuum crystallizing apparatus of the type described, which comprises in combination, a main pipe, means for causing brine to flow continuously through said pipe, a plurality of separate circuits for the brine connected in parallel with said main pipe, a crystallizing vessel in each of said circuits, liquid propelling means for causing the brine to circulate through said circuits, a condenser in the upper part of each of said vessels for condensing the vapours produced therein, another main pipe, 25 means for causing mother water to flow continuously through said last mentioned main pipe, a plurality of separate circuits connected in parallel with the last mentioned main pipe, each of the last mentioned circuits being arranged to feed 30 mother water as a refrigerating liquid to each of said condensers respectively, vacuum producing means, and a plurality of pipes connected in parallel with the vacuum producing means and opening each into the upper part of each of said vessels 35 respectively.

40 13. A vacuum crystallizing apparatus of the type described, which comprises in combination, an inlet tank for the hot brine, an outlet tank, a main pipe for connecting the inlet tank to the outlet tank in such manner that brine is caused to flow continuously through said main pipe, a plurality of separate circuits for the brine connected in parallel with said main pipe, pumping means in each of said circuits for circulating brine from said 45 main pipe through said circuit, and means for applying a vacuum to a portion of each of said circuits for evaporating the brine.

50 14. A vacuum crystallizing apparatus of the type described, which comprises in combination, an inlet tank for the hot brine, an outlet tank, a main pipe for connecting the inlet tank to the outlet tank in such manner that brine is caused to flow continuously through said main pipe, a plurality of separate circuits for the brine connected in parallel with said main pipe, pumping means in each of said circuits for circulating brine from said 55

main pipe through said circuit, vacuum producing means, and means for connecting a portion of each of said circuits in parallel with said vacuum producing means.

15. A vacuum crystallizing apparatus of the type described, which comprises in combination, an inlet tank for the hot brine, an outlet tank, a main pipe for connecting the inlet tank to the outlet tank in such manner as to cause brine to flow continuously through said main pipe, a plurality of separate circuits for the brine connected in parallel with said main pipe, a pump in each of said circuits for causing brine from said main pipe to circulate through said circuit, condensing means in each of said circuits, a main for feeding refrigerating liquid to all of said condensing means, a vacuum pump, and means for connecting a portion of said circuits in parallel with said vacuum pump.

20 16. A vacuum crystallizing apparatus of the type described, which comprises in combination, an inlet tank for hot brine, an outlet tank, a main pipe for connecting the inlet tank to the outlet tank in such manner as to cause brine to flow continuously through said main pipe, a plurality of separate circuits for the brine connected in parallel with said main pipe, a pump in each of said circuits for causing the brine from said main pipe to circulate through said circuit, condensing means in each of said circuits, a main for feeding refrigerating liquid to all of said condensing means, a vacuum pump, and a plurality of pipes connected in parallel with said vacuum pump and opening each into one of said circuits respectively at a part thereof remote from the first mentioned main pipe.

25 17. A vacuum crystallizing apparatus of the type described, which comprises in combination, an inlet tank for hot brine, an outlet tank, a main pipe for connecting the inlet tank to the outlet tank in such manner as to cause brine to flow continuously through said main pipe, a plurality of separate circuits for the brine connected in parallel with said main pipe, a pump in each of said circuits for causing brine from said main pipe to circulate through said circuit, a crystallizing vessel in each of said circuits, a condenser in the upper part of each of said vessels for condensing the vapours produced therein, another main pipe, means for causing mother water to flow continuously through the last mentioned main pipe, a plurality of separate circuits connected in parallel with the last mentioned main pipe, each of the last mentioned circuits being arranged to feed mother water as a refrigerating liquid to each of said condensers respectively, a vacuum pump, and a plurality of pipes connected in parallel with the vacuum pump and opening each into the upper part of each of said vessels respectively.

60

JACQUES WALTER.
